(Cl. D13—1)

To all whom it may concern:

Be it known that we, Corwin Booth, Mark Falk,
and Alfred Christensen, citizens of the United
States, residing at Oakland, San Mateo, and San
Francisco, State of California, respectively, have
invented a new, original, and ornamental Design
for a Building, of which the following is a specific-
ation, reference being had to the accompanying
drawings, forming a part hereof:

Fig. 1 is a top plan view of a building, showing
our new design.

Fig. 2 is an elevational view of one side of the
building, the opposite side being the same in ap-
pearance.

Fig. 3 is an end view of the building as seen
from the left hand end of Fig. 2.

Fig. 4 is an end view of the building as seen
from the right hand end of Fig. 2.

Fig. 5 is a perspective view of the building.

We claim:

The ornamental design for a building, as shown
and described.

CORWIN BOOTH.
MARK FALK.
ALFRED CHRISTENSEN.
